KITCHEN SINK AND DEPOSITORY

John Gutmann, St. Albans, N. Y.

Application April 12, 1932, Serial No. 604,683

8 Claims. (Cl. 4—188)

This invention relates to improvements in a kitchen sink and depository.

One object of this invention is to provide a cabinet-like structure of a sink which may be built into the wall of a room or kitchen.

Another object is to have the sink proper hinged to the cabinet frame, to swing thereon.

A further object is to conceal the sink when not in use so as to improve the appearance of the wall and room and at the same time save space in the room.

Another object is to provide the sink cabinet as well as the sink itself with openings or channels to a depository in such a manner that a deposit of refuse may be made regardless of whether the sink is in an open or closed position.

Another object is to provide a sink and depository with a number of conveniences generally found useful while working at the same.

In the drawings, Fig. 1 is a front elevation of an assembled sink and depository mounted against the wall of a kitchen in a closed condition.

Fig. 2 is a front elevation of an assembled sink and cabinet shown in an open position.

Fig. 3 shows a sectional side elevation on line 3—3 of Figure 2 and a depository connected with the cabinet.

Fig. 4 is a partial plan view of the sink on lines 4—4 of Figure 2.

Fig. 5 is part of a sectional side elevation through sanitary chute with sink in closed position.

Fig. 6 illustrates a detailed construction of a pipe connection.

Fig. 7 is a diagrammatic plan view showing sink with modified form of connection.

Throughout the views the reference numerals apply to corresponding parts.

Referring to the drawings a steel cabinet 10 is fastened to within a wall 11 in such a manner that part of its open end 12 will partly protrude from the outer surface 13 of wall 11. To the lower part of open end 12 is hinged a sink vessel or water container 15 by means of pins, rivets or screws 14, permitting said sink to swing on said cabinet and to be placed in an open or closed position accordingly.

To retain sink or container 15 in a horizontal or level position the rear end of the sink or container is provided with two extensions 16 bearing against supports 17 which form a part with the sidewalls of the cabinet and may either be welded to these walls, or pressed out therefrom or formed and secured in any other suitable manner.

Strainer 19 at the bottom surface of the sink

is connected with an outlet 20 which may form a pipe as shown or be a part of the false bottom 21 located below the bottom 22 of the sink proper.

Outlet 20 has a pipe fitting 23, the centre of which is in line with the centre of the hinge 60 parts 14.

The other end of fitting 23 is connected with a bent pipe 24 extending toward the rear wall 25 of cabinet 10 and from there down and out of the cabinet, where it is fitted to a U-trap 26, which in turn is connected to a sewer pipe 27.

Pipe fitting 23 consists of a coupling 28 screwed to the cylindrical tapered end 29 of outlet 20 and pressing the flange 31 of pipe 24 against a leather washer 32. Coupling 28 which fits tight on the thread of the end 29, is adjusted to permit the coupling 28 and outlet 20 to partially rotate on flange 21 without loosening thread and thereby permitting any water to escape from the fitting.

It is thus possible to swing the sink on its hinges and drain the same through a pipe connection directly attached to a sewer pipe.

A modified form of connection is shown in Figure 7. The flexible connection 60 made from any suitable material couples outlet 20 to pipe 24. It is understood that any other suitable connection may be used.

The upper part of rear wall 33 of sink or vessel 15 has an extension or border 34 which serves the purpose to prevent any water which might have remained in the sink basin, to flow out of same, while the sink is being lifted and placed in a closed position.

While the sink is thus located it is prevented from being swung downward by means of a spring catch or lock 35 held to the upper wall of cabinet 10. This catch engages a notch 36 in sink 15. In order to release the latter, knob 37 forming part of the catch is to be raised.

To the inner surface of the rear wall of cabinet 10 are fastened the conventional hot and cold water faucets 38 and 39 connecting with a swingable spout 40.

Faucets 38, 39 are joined to respective water pipes 41, 42 which passing through the upper or top wall of the cabinet connect with the respective hot and cold water systems 43, 44.

To one side of the cabinet and to the lower or bottom wall 45 thereof is connected a depository chute 46, which either may lead into an incinerator in the cellar of the building or into a paper bag 47 as shown, which may be clipped onto the end of the chute in any suitable manner.

The chute may also lead of course to a can or

other receptacle which may be entered through a door 48 located on wall 11 and near the floor.

Through this chute will pass all refuse such as garbage leavings etc. While the sink is located open, the refuse will be deposited directly into the chute, which on account of its convenient location, will serve to simplify and lighten the work of the person laboring at the sink. To prevent the refuse odor from coming up the chute a spring actuated trap door 61 is provided in any convenient location.

While the sink is located closed, refuse may be deposited into chute 46 through a door 50 located and hinged to the outer surface or false bottom 51 of sink or vessel 15.

All modern sinks possess one or two drain boards 52 located to the sides of the basin, providing a large empty space between each drain board and outer surface 51. This space has been utilized to provide an auxiliary depository chute 53, which will directly connect with the opening of chute 46, without however changing the size or shape of board 52.

Door 50 which may be furnished with two side-walls 55, so as to guide the refuse into the chute, is held in a closed position by means of a spring catch 56.

It will be seen that the sink cabinet shown and described is a unit of exemplary utilities, and which not alone is a compact and self-contained device, easy to install, but also an appliance which is convenient, saves labor, is sanitary, saves space and improves the appearance of the room in which it is located.

This sink cabinet can readily be applied in places where the available space is limited and the permanent appearance of a kitchen sink is undesirable.

I have thus provided a concealed kitchen sink and sanitary depository adapted to be built-in the conventional wall of a room and adapted for use in places where space is limited, such as for example, kitchens, kitchenettes, lunch-wagons, apartment-houses, and apartment-hotels, factories, clubs, schools, institutions, etc.

I have thus further provided a concealed kitchen sink and sanitary depository, comprising faucets, drains, pipes, chutes, and other elements, etc. disposed within a cabinet-like recess formed in a vertical wall, when the device is not in use, and which is so adapted to be swung to operative position when the device is ready for use.

In the accompanying drawings I have illustrated the invention embodied in one of its practical commercial forms but as this illustration is primarily for purposes of disclosure it will be understood that the invention is not limited to this particular form of structure and that it may be modified in many respects without departure from the true spirit and scope of the invention as herein defined and claimed.

I wish it further understood that the terms which I have employed herein are used in a descriptive rather than in a limiting sense, except however for such limitations that may be imposed by the state of the prior art.

Having thus described my invention, what I claim as new and desire to secure by Letters Patent, is:—

1. A closure for combined sink receptacle and refuse depository comprising a swingable cover for the receptacle, a vessel fixedly arranged on the cover, said cover being provided with an enclosure communicating with said depository, the

said enclosure having an opening at the front of said cover through which refuse may be deposited into said enclosure.

2. A closure for a sink having a frame, comprising a cover hingedly connected to said frame at its open front, a vessel arranged on said cover, the bottom of said vessel being spaced from said cover and having an outlet opening, outlet pipe fittings projecting within the space between said bottom and said cover and communicating with said outlet opening, the projecting pipe fittings being adapted to move with said cover while the latter is being swung to open or closed position. 80

3. A closure for a combined sink cabinet and refuse depository chute comprising a cover hingedly connected to the front of said cabinet, a vessel arranged on said cover, the bottom of said vessel being spaced from said cover and having an outlet opening, outlet pipe fittings projecting within the space between said bottom and said cover and communicating with said outlet opening, said cover being provided with an enclosure communicating with said chute, the said enclosure having an opening at the front of said cover through which refuse may be deposited into 90 said enclosure. 95

4. A closure for a combined sink cabinet and refuse depository chute comprising a cover hingedly connected to the front of said cabinet, a vessel arranged on said cover, the bottom of said vessel being spaced from said cover and having an outlet opening, outlet pipe fittings projecting within the space between said bottom and said cover and communicating with said outlet opening, a drain board on said cover and located at a side of said vessel, a space being formed between said board and said cover and communicating with said chute, and a door arranged on said cover through which refuse may be deposited into 100 said latter space when the said cover is in 105 closed position. 110

5. A closure for a combined sink cabinet and refuse depository chute comprising a cover for said cabinet, said cover being hingedly connected to said cabinet at its bottom to adapt said cover 120 to be swung with relation to said cabinet to an open or closed position, a vessel arranged on said cover, the bottom of said vessel being spaced from said cover and having an outlet opening, outlet pipe fittings projecting within the space between said bottom and said cover and communicating with said outlet opening, said fittings including a coupling for adapting the said projecting part thereof to read while said cover is being swung to open or closed position, a drain board located at a side of said vessel, a space being formed between said drain board and said cover to provide a passage connecting with said chute, and a door arranged on said cover through which refuse may be deposited into said passage when 130 the said cover is in closed position. 135

6. A closure for a combined sink cabinet and refuse depository chute comprising a hinged cover for said cabinet, a vessel fixed to said cover, the bottom of said vessel being spaced from said cover, and having an outlet opening, outlet pipe fittings projecting within the space between said bottom and said cover and communicating with said outlet opening, said fittings including a coupling in axial alinement with the cover hinge, said coupling being adapted to permit part of said fittings to rotate with respect to the other thereof, a drain board located at a side of said vessel, a space being formed between said drain board and said cover to provide a passage communicat- 140 145 150

ing with said chute, and a door arranged on said cover through which refuse may be deposited into said passage when the said cover is in closed position, the said door being provided with side walls to guide the refuse into said chute.

7. A closure for a combined sink receptacle and refuse depository comprising a swingable cover for the receptacle, a basin provided in said cover, and a chute in said cover for communicating with

said depository when said cover is in closed position.

8. A closure for a combined sink receptacle and refuse depository comprising a swingable cover for the receptacle, said cover being provided with a basin, and means for depositing refuse when the cover is in closed position, said means being adapted for communication with said depository.
